G. Hamel,
Safety Pocket.

No. 60720

Patented. Jan. 1. 1867.

George Hamel

Charles H. Evans

United States Patent Office.

GEORGE HAMEL, OF ABINGTON, PENNSYLVANIA.

Letters Patent No. 60,720, dated January 1, 1867; antedated December 30, 1866.

IMPROVEMENT IN SAFETY-POCKETS.

The Schedule referred to in these Letters Patent and making part of the same.

TO ALL WHOM IT MAY CONCERN:

Be it known that I, GEORGE HAMEL, of Abington, Montgomery county, in the State of Pennsylvania, have invented a new and improved Mode of Detecting Pickpockets; and I do hereby declare that the following is a full and exact description thereof, reference being had to the accompanying drawings and the letters of reference marked thereon.

Figure 1 is a perspective view of the pickpocket detector.

Figure 2 is a plan of the bottom of the same, showing the seam which fastens it on the stuff the pocket is made of.

The nature of my invention consists in providing any pocket into which one will carry his money or portemonnaie with a metallic box, into which the money or portemonnaie is placed, said box being fastened by a seam, or otherwise, at the bottom, and inside the mentioned pocket.

To enable others skilled in the art to use and make my invention, I will proceed to describe its construction and operation.

I construct a metallic box of any light and resisting material, such as tin, German silver, silver-plated, gold, or gold-plated, in the form as shown in A, fig. 1, or any suitable size or shape, so as to fit into any ordinary-sized pocket of either pants, coat, or waistcoat. Said box, as shown in fig. 1, is provided with a lid, L L, set up on hinges, z z, and fastening, closed by means of knob and spring, P m. The box is sewed in the bottom of the pocket, as shown in figs. 1 and 2, in S S, and, thus disposed, the money is placed into it. Now, having taken care to place the box, A A, so as to have the opening movement of lid, L L, to take place toward me, if any pickpocket introduces his hand into my pocket to steal whatever may be into it, he will either pull out my whole pocket or, pressing unaware on spring-knob P m, open the lid, which, thrown back by means of stiff spring S T, will hit me, thus warning me in time to catch the thief.

I am aware that spring boxes, and springs combined with boxes, or boxes shaped as the one I describe, have been already patented, and I do not claim anything on them, but what I claim as an improved and new article of manufacture, is—

A box of any suitable shape and size with spring lid, fastened by seam or otherwise to the bottom of any pocket, for the purpose hereabove described.

Witnesses:

C. D. COLLADAY,
CHARLES H. EVANS.

GEORGE HAMEL.
